UNITED STATES PATENT OFFICE.

ANTON SCHAD, OF MANSFIELD, OHIO.

SUSPENDERS.

No. 894,907.

Specification of Letters Patent.

Patented Aug. 4, 1908.

Application filed September 9, 1907. Serial No. 392,081.

To all whom it may concern:

Be it known that I, ANTON SCHAD, citizen of the United States, residing at Mansfield, in the county of Richland and State of Ohio, have invented certain new and useful Improvements in Suspenders, of which the following is a specification.

My invention relates to a combined suspender link and pencil holder.

10 The objects of my invention are to provide a means of holding and retaining a pencil or the like upon a suspender to permit the wearer to have ready and convenient use of the pencil when desired.

15 It comprises a link made of suitable material with holders formed on one or both sides of the link to retain the pencil or the like in a convenient place when not in use.

Similar letters of reference refer to similar 20 parts throughout several views.

I attain these objects by the construction illustrated in the accompanying drawing in which:—

Figure 1 is a front plan view of my device 25 showing two ordinary pencils inserted in the holding devices. Fig. 2 is a detail plan view of the combined link and holders showing the shape of the blank before bending or looping into shape. Fig. 3 is a vertical cross-sectional view of my device showing the method 30 of looping the ends of the blank and its relation to the other parts when combined together for the purpose intended.

In the construction of my link and pencil 35 holder, I prefer to form the blank (1) out of leather substantially of the shape shown. The web 2 of the suspender is looped in the ordinary manner and a bail 3 suspended thereby in the usual way. The outwardly 40 projecting portions 4 and 5 of the blank are not made at right angles with the body portion 1 but depend downward at a slight inclination therewith so that when they are folded together they form holding devices 6 45 and 7 having tapered apertures into which the pencils 8 and 9 are inserted and retained in place.

The purpose of forming the holding device 50 with tapered apertures is to permit the pencil to be inserted in the aperture easily and

without inconvenience and at the same time provide means of frictionally holding the pencil in place by making the lower end of the orifice slightly less in diameter than the ordinary pencil whereby close frictional 55 contact can be maintained at all times between the outer periphery of the pencil or the like and the inner periphery of the apertures. This construction permits of rapid insertion but is not absolutely essential. In 60 assembling the link for the purpose of attaching it to the bail 3 the horizontal arms 4 and 5 are made to overlap each other forming the holding devices 6 and 7 as shown in Fig. 1 and the upper portion 10 is passed 65 around the horizontal bar of the bail 3 and turned down on the arms 4 and 5, and the overlapped parts are securely connected together by means of the combined rivet and button 11 which passes through suitable 70 apertures formed in the projecting portions described. A button clasp 12 is securely attached to the portion 13 of the blank and when the end 13 is looped the clasp is adapted to engage with the button 11 forming a 75 loop 14 to suspend the suspender strap 15.

I prefer to make the blank integral and of leather but it is apparent however that it can be made of two or more pieces and of elastic material without departing from the 80 principle of my invention.

Having fully described my invention what I claim and desire to secure by Letters Patent is:—

1. A suspender end comprising a link 85 adapted to connect with a strap and provided with means on each side thereof for holding a pencil or the like as and for the purpose set forth.

2. An article of manufacture comprising a 90 link for a suspender end adapted to connect with a suspender strap, outwardly extending wing portions formed on and at an incline to the body portion of the link to provide tapered holding means for a pencil or the 95 like.

3. The combination of a suspender link and holding means for a pencil or the like comprising a blank formed substantially cross shape to provide means to connect with 100

a suspender strap and form pockets thereon as described and set forth.

4. In a pencil holding device for suspenders, a blank formed substantially to conform to the shape of a cross with the horizontal arms formed at an inclination to the body portion by means of which said arms when folded and connected to the body portion

form tapered apertures for the purpose set forth.

In testimony whereof I affix my signature in presence of two witnesses.

ANTON SCHAD.
